UNITED STATES PATENT OFFICE.

J FRANK ALLARD, OF BROOKLYN, NEW YORK, ASSIGNOR TO UNDERWOOD TYPEWRITER COMPANY, OF NEW YORK, N. Y., A CORPORATION OF NEW JERSEY.

TYPE-WRITING MACHINE.

No. 924,525.

Specification of Letters Patent.

Patented June 8, 1909.

Application filed March 20, 1909. Serial No. 484,690.

To all whom it may concern:

Be it known that I, J FRANK ALLARD, a citizen of the United States, residing in Brooklyn, in the county of Kings and State 5 of New York, have invented certain new and useful Improvements in Type-Writing Machines, of which the following is a specification.

This invention relates to typewriting machines, which are especially constructed to facilitate the writing of bills and simultaneously recording them, in a manner commonly known as "condensed charging;" a mechanism of this kind being illustrated in 15 United States Letters Patent No. 889,855 granted to J. G. McLaughlin, June 2, 1908.

In the operation known as "condensed charging," after the writing of a bill is completed, the platen is turned backwardly a 20 considerable distance, the written bill is withdrawn, a fresh bill head is inserted, and then the platen is rotated forwardly to its initial position. During these operations the record sheet and carbon sheet remain in 25 the machine; and the first line of writing on the new bill directly follows the last line of writing on the first bill, so that the necessity is avoided of leaving a gap between the entries on the record sheet to correspond with 30 the depth of the heading on the printed bill head. This special backward and forward rotation of the platen is usually effected by a crank, which rotates about the platen axis, playing between stops provided upon the 35 platen frame. The rotation of this crank is limited to a little less than an entire revolution; but in practice this is found sufficient for ordinary bill heads.

Where the depth of the printed portion of 40 the bill head exceeds the circumference of the platen, and it is consequently necessary for the platen to turn backwardly more than an entire revolution at a single stroke, it has been proposed to employ movement-multiplying gearing between the crank and the 45 platen, so that a stroke of the crank through less than an entire revolution will turn the platen through more than an entire revolution.

50 One of the principal objects of the present invention is to provide for the rotation of the platen-driving crank itself through more than an entire revolution at one stroke, so that it may be connected directly to the

platen, thus avoiding the necessity of employing gearing.

In carrying out the invention in one form, the platen-driving crank is mounted to rotate about the platen axis, and its movements are limited by a stop mechanism possessing novel features. The crank is provided with a dog or pawl to engage a notched wheel which is fixed to the platen axle and hence to the platen. A stop is provided for limiting the initial stroke of the crank, 60 wheel and platen, but the crank is enabled during its first revolution to pass freely by said stop, and is arrested thereby upon a second revolution in the same stroke; the exact point of arrest being determined by the position to which the stop is adjusted around the 65 platen axis. Another stop is provided for limiting the return stroke of the driver and platen to initial position, but the crank is enabled during its first return revolution to 70 pass freely by its return stop, which finally arrests the crank and platen upon return thereof to initial position. Thus the stroke 75 of the crank about the platen axis is considerably lengthened over prior devices, and the movement of the platen is made correspondingly greater, so as to accommodate 80 bills which have extraordinary depths of printed headings.

Provision is made for automatically disconnecting the crank from the platen upon their return to initial positions, to permit subsequent line-feeding operation of the platen independently of said crank or driver. Provision is also made for rendering the 85 initial stroke of the platen shorter than the return stroke thereof, to secure automatically the line-space between entries on the record sheet; certain mechanism for this purpose being disclosed in said patent. Certain features herein illustrated are disclosed 90 in pending United States application No. 478,675. Provision is also made for limiting the stroke of the crank to less than an entire revolution at will, so as to accommodate 95 bills having short headings thereon.

In the accompanying drawings, Figure 1 is a perspective end view of the platen frame and platen of the well known Underwood front strike writing machine with the present 100 improvements applied thereto; the platen-driving crank being shown as having entered upon its second revolution from initial

position. Fig. 2 is a part sectional plan of the platen, platen frame and line-spacing devices of said machine; the parts shown in normal positions. Fig. 3 is a sectional plan 5 of the platen-controlling devices seen at Fig. 1; the parts shown in normal positions. Fig. 4 is a perspective view of a latch forming part of the mechanism for securing automatically a space between entries on the record sheet. Fig. 5 is a perspective view of the platen-driving pawl or dog. Fig. 6 is a perspective view of the platen-driving ratchet wheel. Fig. 7 is a perspective view of a loose interponent placed between the platen-driving crank and the crank-arresting stop, to cause the arrest of the crank by the stop. Fig. 8 is a perspective view of a circular 10 stop-rack fixed to the platen frame and carrying the pivoted latch seen at Fig. 4 and the pivoted stop-arm seen at Fig. 11. Fig. 9 is a perspective view of one end of the platen shaft and certain devices carried thereon. Fig. 10 is a fragmentary view of a rack device seen at Fig. 1, but with the pivoted 15 members omitted. Fig. 11 is a perspective view of a pivoted stop arm for arresting the platen-driving crank on its return to initial position. Fig. 12 is an end elevation showing the parts approximately in normal positions and illustrating by a dotted arrow the extent of movement of the platen-driving crank from initial position. Fig. 13 shows the platen-driving crank arrested after making the stroke indicated by the arrow at Fig. 16. Fig. 14 is an elevation to indicate the movement of a projection on the platen-driving pawl to engage an interponent, and thereby enable the latter to arrest the platen; said projection being shown in cross-section. Fig. 15 is a diagram to illustrate the manner in which the platen-driving pawl is caused to move into engagement with the platen-driving notched wheel. Fig. 16 shows the devices at Fig. 13, but omitting the crank. Fig. 17 is an elevation illustrating the escape of the pawl projection from the annular 20 guide which holds the pawl in engagement with the platen-driving wheel. Fig. 18 is an elevation showing the operation by the pawl projection of the stop arm, which, at the completion of the return stroke of the crank, is engaged by said projection to arrest the crank. Fig. 19 is a plan of certain parts seen at Fig. 3. Fig. 20 is a view similar to Fig. 12, but indicating by a curved arrow a short stroke of the platen from initial position. Fig. 21 shows the crank arrested at a point indicated by the arrow at Fig. 20. At Fig. 13 the crank is arrested by one stop, and at Fig. 21 by a different stop, the latter being in ineffective position at the Fig. 13 operation.

The usual platen 1 of an Underwood type-writing machine is rotatably mounted by means of an axle 2 in the ends 3 of the platen

frame, the ends of the axle projecting through the ends of the platen frame end and having finger wheels 4 thereon, by means of which the platen may be rotated forwardly or backwardly to an unlimited extent. The platen is also provided with the usual toothed line-space wheel 5, which is engaged by a yielding 70 detent 6 to hold the platen steady when writing. The line-space wheel is advanced intermittently by means of a pawl 7 and a lever 8.

Upon the end of the platen axle 2 is fixed a hub 9 of a wheel 10 having teeth 11 corresponding in number to the teeth of the line-space wheel 5. The hub has a flattened portion 9^a to fit a corresponding opening 11^a in the wheel; the hub also having a dowel 9^b to fit an opening 11^b in the wheel, Figs. 6 and 9. The wheel 10 is rotated by means of a pawl or dog 12 pivoted at 13 upon a crank 14 having a finger piece 15. The tooth 16 of the pawl is normally disengaged from the wheel 10, as at Fig. 20, to permit independent rotation of said wheel and crank. A pin 17 projecting from the pawl 12 normally occupies a segmental recess 18 in an annular rim 19, the latter provided upon a disk 20, which is connected by a tie-rod 21 to the platen frame end 3. The pin 17 normally overlies a trip or latch 22 formed upon the side of a small disk 23, having a pivot or stem 24, whereby it is mounted in a circular recess 25 formed in the fixed disk 20. The small disk 23 has a pin 26 to engage a slot 27 in the fixed disk 20, (Figs. 4 and 10) to limit the oscillating movements of the small disk and hence of the latch or trip thereon. A spring 28 is coiled about the stem 24 (Fig. 3) and engages the pin 26 to return the trip-disk to normal position. The threaded stem 24 has a nut 29, in the form of a cap to inclose the pin 26 and spring 28 and to hold the latch or trip mechanism in place.

When the crank 14 is swung forwardly, the pin 17 rides down the forward inclined edge 30 of the recess 18, and presses down upon the trip 22, causing the trip-disk 23 to oscillate, Fig. 15; and the tooth 16 of the pawl is caused to engage a tooth 11 of the wheel 10, the pawl moving from the Fig. 20 to the Fig. 15 position. The pawl is held in engagement with the toothed wheel by means of the pin 17, which rides along the inner side of the annular rim 19. As soon as the pin 17 leaves the recess 18, the trip is returned to normal position (Figs. 1, 8 and 21) by means of the spring 28. The continued forward movement of the crank 14 swings the wheel 10 and platen 1 around until the crank is arrested by an adjustable stop which will be presently described. The crank is then swung backwardly together with the wheel 10 and the platen; but the backward movement of the wheel and platen is prolonged beyond the forward end of the recess 18, by reason of the 130

pin 17 riding along the under side of the trip 22, which forms a continuation of the annular rim 19.

A spring 34 coiled about the pawl pivot 13 tends, constantly to swing the pawl outwardly from the wheel 10; and when, during the return motion of the crank, the pin or projection 17 on the pawl arrives opposite the gap between latch 22 and the opposite 10 end of the recess 18, said spring 34 snaps the pawl up from the wheel, the pin 17 entering the recess 18, as at Figs. 3 and 17. The return stroke of the crank, Fig. 17, is limited by the engagement of said pin 17 with the 15 stop-arm 36. It will be seen that one surface of the latch 22 forms a continuation of the annular guide 19, and it will be understood that during the return stroke of the platen the pawl 12 is maintained in engagement 20 with the platen wheel 10 for an additional time, while the projection 17 is running along said surface of the latch 22, so that this stroke of the platen is longer than the initial stroke thereof, to secure a blank space be- 25 tween entries on the record sheet.

A succession of notches 37 is formed in the outer edge of the annular guide 19 to form a circular rack for an adjustable pin stop 38. This stop, however, does not project into the 30 path of the crank 14 or pawl 12; so that during the first revolution of the crank from the initial position at Fig. 12, the crank and pawl pass freely by the stop 38. Upon the second revolution of the crank at one stroke in the 35 same direction, an interponent 39 comes into play; said interponent in the form of an arm hung loosely upon the hub 9 and lying against the face of the annular guide 19, between said guide and the wheel 10, and in 40 position to engage the stop 38. The projecting pin 17 on the pawl 12 extends far enough to engage said interponent. Thus by the intervention of the latter the arrest of the crank 14 is effected. It will be under- 45 stood that during the return stroke of the crank, the pin 17 will engage the interponent 39 upon the opposite edge of the latter, and then swing the same idly around the hub 9; said interponent performing no function 50 upon said return stroke. The stop 38 projects from an arm 40, which has a hub 41, loosely engaging the main hub 9; said hub being retained by a collar 42 secured on the hub 9 by a screw 43, Fig. 3. The stop pin 55 38 projects from a stem 44 carrying at its outer end a button 45, and at its inner end a nut 46 which fits the inner surface of the tubular arm 40. By means of the finger-piece 45 the stem 44 and stop 38 may be drawn 60 upwardly, for convenience in adjusting the stop to a different notch 37 in the rack; and a spring 47, compressed between the nut 46 and a partition 48 in the tubular arm 40, serves to draw the stop 38 down into the 65 notch. Said return stop 38 is normally in

the path of said pin 17 projecting from the pawl 12; but when the crank is completing the first revolution, the pin 17 engages the other side of the stop-arm 36 and swings it about its pivot 49 to the position at Fig. 1, 70 where it is not only ineffective to arrest the crank, but also serves as a switch or bridge to close the gap between the latch 22 and the end of the recess 18 in the annular guide 19, so that the projection 17 is prevented at this time from reentering said recess 18, and instead of doing so rides along toward the left upon the latch 22 (Fig. 14) and upon the inner guiding surface of the guide 19, until the crank is arrested by means of the interponent 39, as already explained. Thus the pawl is automatically maintained in engagement with the platen-driving wheel 10 during more than an entire revolution of said wheel in one direction. 85

During the return of the crank from the position at Fig. 13, the pin 17 projecting from the pawl engages a cam 50 (Fig. 18) formed upon the stop-arm 36, and returns the latter to normal position. A spring 51 secured by a screw 52 upon the periphery of the guide 19 serves to detain the stop-arm 36 in either normal or gap-closing position. It will now be understood that upon swinging again around the platen axis to initial 95 position, the crank is finally arrested by the stop 36, as at Fig. 17; the pawl-projection 17 first riding over the latch 22 for the purpose of rendering the return stroke of the platen longer than the initial stroke thereof, as already explained. 100

It will be seen that the stop 38 arrests the driver only after the latter has turned through more than an entire revolution at one stroke from the initial position at Figs. 3 and 12; said driver passing the stop 38 once, but being arrested at a succeeding revolution by means of the interponent 39; that the stop 36 is moved by the returning driver into position to arrest said driver after the latter has turned through more than an entire revolution from the position at Fig. 13; that by a single stroke the driver is both connected to the platen, as at Fig. 12, and turned through more than an entire 110 revolution; and upon return to initial position is automatically disconnected from the platen by the spring 44; and that the stop-carrying arm 40 is upon one side and the wheel 10 upon the other side of the rack or 115 notches 37. It will also be seen that the part 14, since it co-operates with the stop 38 to arrest the platen, may be regarded as a stop-member connectible at will to the platen for rotation therewith, to co-act with the stop-members 38 and 36 to limit the rotation of the platen in forward and backward directions; and that the wheel 10 may be regarded as a clutch-member, and the 120 pawl 12 with the crank 14 as a co-operating 125 130

clutch member, whose engagement is mechanically maintained while the platen rotates more than an entire revolution in each direction, and mechanically broken upon the 5 return of the member 14 to initial position.

The parts 36, 50 may be regarded as a tripping device, to relieve the projection 17 from the control of the guide 19 at the return of the crank, said tripping device comprising a 10 pivoted switch 36, which temporarily forms part of the guide 19, and has a cam or arm 50 movable by the crank 14 to throw the switch.

When it is desired to use the machine for bills having short printed headings, the interponent 39 is thrown down to the idle position at Fig. 20 or 21, and the finger-piece 15 45 is pulled out to withdraw the stop 38, and is then turned about its own axis to move said stop 38 to an ineffective position, and to 20 bring into play another stop 53, which is of greater length than 38, and sufficiently long to stand in the path of a shoulder 54 formed on the pawl 12 to arrest the latter and hence the crank and platen, as at Fig. 21, before the 25 crank turns through an entire revolution from initial position, as at Fig. 20. Thus the device may be used for either long or short bill heads, as required. Either stop 38 or 53 may be set into the notches 37.

30 Variations may be resorted to within the scope of the invention, and portions of the improvements may be used without others.

Having thus described my invention, I claim:

35 1. In a typewriting machine, the combination with a revolute platen, of a driver therefor, said driver mounted to turn around the axis of the platen, and a device operative to arrest the driver only after the latter has 40 turned through more than an entire revolution at one stroke from initial position.

2. In a typewriting machine, the combination with a revolute platen, of a revolute driver therefor, a stop past which said driver 45 may move, and means to enable said driver, after passing the stop once, to be arrested thereby at the succeeding revolution of the driver in the same direction.

3. In a typewriting machine, the combination with a revolute platen, of a revolute driver therefor, a stop out of the path of said driver, and a loose interponent to engage said stop and said driver to arrest the latter upon the second revolution thereof in the same direction at one stroke.

4. In a typewriting machine, the combination with a revolute platen, of a revolute driver therefor, a stop out of the path of said driver, and a loose interponent to engage said stop and said driver to arrest the latter upon the second revolution thereof in the same direction at one stroke, said interponent being freely movable by said driver during the return stroke of the latter to initial position.

5. In a typewriting machine, the combina-

tion with a revolute platen, of a revolute driver for the platen, and a device movable by said driver into position to arrest the driver after the latter has turned through more than an entire revolution from normal position. 70

6. In a typewriting machine, the combination with a revolute platen, of a revolute driver for the platen, a device movable by said driver into position to arrest the driver after the latter has turned through more than an entire revolution from normal position, and a device movable by said driver, during the return stroke thereof, into position for arresting the driver upon return thereof to 80 initial position.

7. In a typewriting machine, the combination with a platen and a stop, of a driver normally disconnected from the platen and capable of turning about the platen axis to an extent determined by said stop and in excess of 360°, and means for enabling a single stroke of the driver both to connect it to the platen and to effect rotation of the latter through more than an entire revolution until arrested by said stop. 85

8. In a typewriting machine, the combination with a revolute platen, of a notched wheel connected thereto, a driver having a pawl or dog to engage the notched wheel, a stop out of the path of said crank, and a loose interponent to engage the stop and effect the arrest of the crank to limit its throw. 95

9. In a typewriting machine, the combination with a revolute platen, of a notched wheel connected thereto, a driver having a pawl or dog normally disengaged from the notched wheel, means to move the pawl into engagement with said wheel to enable the crank to turn the wheel and platen, a stop out of the path of said crank, and a loose interponent to engage the stop and limit the throw of the crank from normal position. 100

10. In a typewriting machine, the combination with a platen, a platen frame, and an axle for the platen, of a curved rack fixed to the platen frame, said axle passing through said rack, a stop adjustable along said rack, an arm upon one side of said rack and carrying said stop and movable about the platen axle, a toothed or notched wheel upon the other side of said rack and fixed to the platen axle, a driver having a pawl to engage said toothed wheel, said stop out of the path of said driver, and an interponent hung loosely upon the platen axle between said wheel and said rack, to engage said stop and arrest said driver. 110

11. In a typewriting machine, the combination with a platen, a platen frame, and an axle for the platen, of a curved rack fixed to the platen frame, said axle passing through said rack, a stop adjustable along said rack, an arm upon one side of said rack and carrying said stop and movable about the platen 115 120 125 130

axle, a toothed or notched wheel upon the other side of said rack and fixed to the platen axle, a driver having a pawl to engage said toothed wheel, said stop out of the path of said driver, and an interponent hung loosely upon the platen axle between said wheel and said rack, to engage said stop and arrest said driver, said driver in the form of a crank, and said wheel mounted between the crank and

10 the rack.

12. In a typewriting machine, the combination with a revolute platen and a revolute driver therefor, of a stop adjustable about the axis of revolution of the driver and out 15 of the path of the driver, and an interponent in the path of the driver and arrestable by said stop, said interponent loosely revolute about the axis of the driver.

13. In a typewriting machine, the combination with a platen, of a member normally disconnected from the platen and capable of a mechanically limited turning movement about the platen axis through more than 25 360° at each stroke and connectible to the platen at will for mechanically limiting the extent of rotation of the latter.

14. In a typewriting machine, the combination with a platen, and a platen frame, of a stop device upon the platen frame, and a 30 device connectible at will to the platen to rotate therewith and constructed to coöperate with said stop device for mechanically limiting the rotation of the platen only after the latter has turned through more than an entire 35 tire revolution at one stroke; a part being included which is adjustable concentrically with the platen to vary the extent of the platen movement.

15. In a typewriting machine, the combination with a revolute platen, of a crank normally disconnected from the platen and mounted to turn about the platen axis, a toothed wheel fixed to the platen, means upon said crank to engage said wheel, means 45 to maintain such engagement during more than an entire revolution of the crank and wheel; the wheel being normally disconnected from the crank, and an adjustable stop for limiting the movement of the crank after the latter has turned more than an entire revolution 50 from initial position.

16. In a typewriting machine, the combination with a revolute platen, of a pawl and ratchet therefor, a driver to operate the platen by means of the pawl and ratchet, and a stop effective to limit the stroke of the driver only after the latter has turned at one stroke through more than an entire revolution from initial position.

17. In a typewriting machine, the combination with a revolute platen, of a pawl and ratchet therefor, a driver to operate the platen by means of the pawl and ratchet, and a stop effective to limit the stroke of the

driver only after the latter has turned at 65 one stroke through more than an entire revolution from initial position, means being provided to maintain the connection between the driver and the platen during the return stroke of the driver to initial position. 70

18. In a typewriting machine, the combination with a platen, of a wheel connected thereto and provided with teeth or notches, a crank mounted to turn concentrically with said wheel, a pawl controlled by said crank, 75 means normally holding said pawl out of engagement with said wheel, means to enable the crank to move the pawl into engagement with the wheel, and means to maintain such an engagement during a stroke of the 80 crank through more than an entire revolution.

19. In a typewriting machine, the combination with a platen, of a wheel connected thereto and provided with teeth or notches, 85 a crank mounted to turn concentrically with said wheel, a pawl controlled by said crank, means normally holding said pawl out of engagement with said wheel, means to enable the crank to move the pawl into engagement with the wheel, means to maintain such an engagement during a stroke of the 90 crank through more than an entire revolution back to initial position, and means to limit the first stroke of the crank. 95

20. In a typewriting machine, the combination with a platen, of a wheel connected thereto and provided with teeth or notches, a crank mounted to turn concentrically with said wheel, a pawl controlled by said crank, 100 means normally holding said pawl out of engagement with said wheel, means to enable the crank to move the pawl into engagement with the wheel, means to maintain such an engagement during a stroke of the 105 crank through more than an entire revolution back to initial position, and means to limit the first stroke of the crank, said limiting means including an adjustable stop which is ineffective during the first revolution of the crank. 110

21. In a typewriting machine, the combination with a revolute platen, of a revolute driver therefor, a device operative to arrest the driver after the latter has 115 turned through more than an entire revolution at one stroke from initial position, and a device operative to arrest the driver upon return movement thereof through more than an entire revolution to initial position. 120

22. In a typewriting machine, the combination with a platen, of a driver rotatable forwardly and backwardly about the platen axis, and relatively adjustable stops for limiting the forward and backward movements of said driver only after the latter has 125 turned through more than a complete revolution at one stroke in either direction; the

platen being normally capable of forward or backward rotation to an unlimited extent independently of said driver.

23. In a typewriting machine, the combination with a revolute platen, of a platen driver mounted to turn about the platen axis, and means, including a stop which is adjustable about the platen axis, for arresting said driver in its forward and back strokes only after it has turned more than a complete revolution in either direction; said arresting means being effective to arrest the platen only when the latter is rotated by means of said driver, and the platen being normally rotatable in either direction at will to an unlimited extent.

24. In a typewriting machine, the combination with a revolute platen, of a driver therefor, a stop for arresting the driver upon its return stroke, means to enable said driver upon its initial stroke to move past said stop, and a device operative to arrest the driver after more than an entire revolution thereof at one stroke from initial position, said driver movable freely past both of said stops during its return stroke to initial position.

25. In a typewriting machine, the combination with a revolute platen, of a driver therefor, a stop for arresting the driver upon its return stroke, means to enable said driver upon its initial stroke to move past said stop, a device operative to arrest the driver after more than an entire revolution thereof at one stroke from initial position, said driver movable freely past both of said stops during its return stroke to initial position, means to connect the driver automatically with the platen at the beginning of its initial stroke, and means for automatically disconnecting the driver from the platen upon reaching the return stop as set forth.

26. In a typewriting machine, the combination with a revolute platen, of a revolute driver normally disconnected from the platen, means to connect the driver to the platen, a device operative to arrest the driver after the latter has turned through more than an entire revolution, and a device operative to arrest the driver upon return movement thereof through more than an entire revolution to initial position.

27. In a typewriting machine, the combination with a revolute platen, of a revolute driver normally disconnected from the platen, means to connect the driver to the platen, a device operative to arrest the driver after the latter has turned through more than an entire revolution, and a device operative to arrest the driver upon return movement thereof through more than an entire revolution to initial position, said driver mounted to turn about the axis of the platen.

28. In a typewriting machine, the combination with a revolute platen and a notched

wheel connected thereto, of a revolute driver having a pawl to engage the notched wheel and enable the driver to rotate the platen more than an entire revolution at one stroke, a stop to arrest the driver upon its return stroke, and means to enable the driver to move said stop out of its path during the initial stroke of the driver and for restoring the stop to normal position during the return stroke of the driver.

29. In a typewriting machine, the combination with a revolute platen and a notched wheel connected thereto, of a revolute driver having a pawl to engage the notched wheel and enable the driver to rotate the platen more than an entire revolution at one stroke, a stop to arrest the driver upon its return stroke, and means to enable the driver to move said stop out of its path during the initial stroke of the driver and for restoring the stop to normal position during the return stroke of the driver, means being provided to detain said stop in each of its normal and abnormal positions.

30. In a typewriting machine, the combination with a revolute platen and a notched wheel connected thereto, a revolute driver having a pawl to engage the notched wheel and enable the driver to rotate the platen more than an entire revolution at one stroke, a stop out of the path of said crank, a loose interponent to engage the stop and effect the arrest of the crank to limit its throw to normal position, a stop to arrest the driver upon its return stroke, and means to enable the driver to move said return stop out of its path during the initial stroke of the driver and for restoring the stop to normal position during the return stroke of the driver.

31. In a typewriting machine, the combination with a revolute platen and a notched wheel connected thereto, a revolute driver having a pawl to engage the notched wheel and enable the driver to rotate the platen more than an entire revolution at one stroke, a stop out of the path of said crank, a loose interponent to engage the stop and effect the arrest of the crank to limit its throw to normal position, a stop to arrest the driver upon its return stroke, and means to enable the driver to move said return stop out of its path during the initial stroke of the driver and for restoring the stop to normal position during the return stroke of the driver, means being provided to detain the last-mentioned stop in each of its normal and abnormal positions.

32. In a typewriting machine, the combination with a revolute platen and a platen frame, of two clutching members, one whereof is connected to the platen and the other whereof is provided with a finger-piece for rotating the platen, stops effective to limit the forward and backward rotation of the

finger-piece after the latter has turned at one stroke through more than an entire revolution, means whereby the clutching members may be maintained in positive engagement 5 during the rotation of the finger-piece at one stroke through more than an entire revolution both away from and back to initial position, and means for effecting automatic release of said clutching members upon the return 10 of said finger-piece through more than an entire revolution to initial position.

33. In a typewriting machine, the combination with a revoluble platen and a platen frame, of a toothed wheel connected to the platen, a crank having a toothed member which is normally out of engagement with said wheel, means to move the toothed member into engagement with the wheel, said toothed member having a projection, and a 20 complete annular or circular bearing concentric with said wheel and engageable by said projection for maintaining the engagement of said toothed member with said wheel during their rotation at one stroke through more than an entire revolution; a tripping device being provided to relieve said projection from the control of said guide at the return of the crank or driver through more than an entire revolution to initial position.

34. In a typewriting machine, the combination with a revoluble platen and a platen frame, of a toothed wheel connected to the platen, a crank having a toothed member which is normally out of engagement with said wheel, means to move the toothed member into engagement with the wheel, said toothed member having a projection, and a complete annular or circular bearing concentric with said wheel and engageable by said 35 projection for maintaining the engagement of said toothed member with said wheel during their rotation at one stroke through more than an entire revolution; a tripping device being provided to relieve said projection from the control of said guide at the return 40 of the crank or driver through more than an entire revolution to initial position, said tripping device comprising a pivoted switch forming part of said guide and having an arm 45 movable by the crank to throw the switch.

35. In a typewriting machine, the combination with a revoluble platen and a platen frame, of a toothed wheel connected to the platen, a crank having a toothed member which is normally out of engagement with said wheel, means to move the toothed member into engagement with the wheel, said toothed member having a projection, and a complete annular or circular bearing concentric with said wheel and engageable by said 55 projection for maintaining the engagement of said toothed member with said wheel during their rotation at one stroke through more than an entire revolution; a tripping device 60 being provided to relieve said projection

from the control of said guide at the return of the crank or driver through more than an entire revolution to initial position, said tripping device comprising a pivoted switch forming part of said guide and having an arm 70 movable by the crank to throw the switch, said switch movable by said arm to a position to arrest the crank upon the return thereof to initial position.

36. In a typewriting machine, the combination with a revoluble platen and a platen frame, of a toothed wheel connected to the platen, a crank having a toothed member which is normally out of engagement with said wheel, means to move the toothed member into engagement with the wheel, said toothed member having a projection, a complete annular or circular bearing concentric with said wheel and engageable by said projection for maintaining the engagement of 80 said toothed member with said wheel during their rotation at one stroke through more than an entire revolution; a tripping device being provided to relieve said projection from the control of said guide at the return 85 of the crank or driver through more than an entire revolution to initial position, said tripping device comprising a pivoted switch forming part of said guide and having an arm 90 movable by the crank to throw the switch, said switch movable by said arm to a position to arrest the crank upon the return thereof to initial position, and a spring to move said projection through a gap in said 95 guide formed by the opening of said switch.

37. In a typewriting machine, the combination with a revoluble platen and a platen frame, of a toothed wheel connected to the platen, a crank having a toothed member which is normally out of engagement with said wheel, means to move the toothed member into engagement with the wheel, said toothed member having a projection, a complete annular or circular bearing concentric with said wheel and engageable by said projection for maintaining the engagement of 105 said toothed member with said wheel during their rotation at one stroke through more than an entire revolution; a tripping device being provided to relieve said projection from the control of said guide at the return 110 of the crank or driver through more than an entire revolution to initial position, said tripping device comprising a pivoted switch forming part of said guide and having an arm 115 movable by the crank to throw the switch, said switch movable by said arm to a position to arrest the crank upon the return thereof to initial position, and a spring to move said projection through a gap in said 120 guide formed by the opening of said switch, said gap or recess having a beveled portion to coöperate with said projection to enable the crank to force the pawl into engagement with the wheel at the beginning of the initial 125 130

movement of the crank, and said recess being partly closed by a latch which forms another part of said guide.

38. In a typewriting machine, the combination with a revoluble platen, of a notched wheel connected thereto, a driving pawl having a pin normally occupying a recess in an annular guide, a pivoted latch partly closing said recess and forming a part of the annular guide, a crank on which the pawl is pivoted, said crank mounted concentrically with said notched wheel, and said recess having a cam portion to coöperate with said pin to enable the crank to throw the pawl into engagement with said wheel, a switch movable by said pin to close said recess at the completion of a revolution of the crank from normal position, to guide the pin to run past said recess and permit the crank to enter upon a second revolution of the notched wheel in the same direction, a stop out of the path of said crank, a loose interponent to engage the stop and effect the arrest of the crank at the completion of the throw thereof from normal position, and an arm upon said switch to enable said pin to open the switch during the return stroke of the crank; said open switch serving as a stop to engage the pin and cause the arrest of the pawl and crank and to direct the pin into said recess at the completion of the stroke of the crank to initial position.

39. The combination with a platen, of a crank normally disconnected therefrom, and means to lock the crank to the platen during the rotation of the crank more than an entire revolution from initial position and back to initial position.

40. The combination with a platen, of a crank normally disconnected therefrom, and means to lock the crank to the platen during the rotation of the crank more than an entire revolution from initial position and back to initial position and then to disconnect the crank from the platen.

41. The combination with a platen, of a crank normally disconnected therefrom, and means to lock the crank to the platen during the rotation of the crank more than an entire revolution from initial position and back to initial position and then to disconnect the crank from the platen, means being provided for rendering the initial stroke of the platen of different length from the return stroke thereof.

42. In a typewriting machine, the combination with a revoluble platen, of a pawl and ratchet therefor, a driver to operate the platen by means of the pawl and ratchet, a stop effective to limit the stroke of the driver only after the latter has turned at one stroke through more than an entire revolution from initial position, means being provided to maintain the connection between the driver and the platen during the return stroke of the driver to initial position; and means be-

ing also provided to cause the return stroke of the platen to exceed in length the initial stroke thereof.

43. In a typewriting machine, the combination with a platen, of a wheel connected thereto and provided with teeth or notches, a crank mounted to turn concentrically with said wheel, a pawl controlled by said crank, means normally holding said pawl out of engagement with said wheel, means to enable the crank to move the pawl into engagement with the wheel, means to maintain such an engagement during a stroke of the crank through more than an entire revolution, and back to initial position, and means to limit the first stroke of the crank; means being provided to disconnect the crank from the platen after the return stroke of the platen has exceeded in length the initial stroke thereof.

44. In a typewriting machine, the combination with a revoluble platen, of two stops, whereof one is provided with means whereby it may be adjusted concentrically with the platen, and a member disconnected from the platen but connectible thereto to rotate about the platen axis for coöperation with said stops to arrest the platen after the revolution thereof through more than an entire revolution at one stroke from normal position, and to arrest the platen upon the return stroke thereof through more than an entire revolution to initial position; provision being made to cause the return stroke of the platen to exceed in length the initial stroke thereof.

45. In a typewriting machine, the combination with a revoluble platen, of a driver therefor, a stop for arresting the driver, said stop mounted to be movable by the driver out of the path of the latter as it enters upon its second revolution in a single stroke, and means for enabling said driver in its return stroke upon passing said stop to set the same into effective position.

46. In a typewriting machine, the combination with a revoluble platen, of a driver therefor, a stop for arresting the driver, said stop mounted to be movable by the driver out of the path of the latter as it enters upon its second revolution in a single stroke, and means for enabling said driver in its return stroke upon passing said stop to set the same into effective position, said stop having a pivot upon which it swings into and out of effective position and also having an arm, and said driver having a projection for moving said stop out of its path, for swinging said stop by means of said arm, and for engagement with the stop to arrest the returning driver.

47. In a typewriting machine, the combination with a revoluble platen, of a driver therefor, a stop for arresting the driver, said stop mounted to be movable by the driver out of the path of the latter as it enters upon

its second revolution in a single stroke, means for enabling said driver in its return stroke upon passing said stop to set the same into effective position, and means to disconnect 5 the driver automatically from the platen upon being arrested by said stop.

48. In a typewriting machine, the combination with a revoluble platen and a wheel connected thereto, of a revoluble driver having a pawl to engage the wheel, means to disconnect the pawl from the wheel automatically upon the return of the driver to initial position, and means to enable the driver to render said disconnecting means ineffective, 10 so as to permit the driver to turn through more than an entire revolution at one stroke without becoming disconnected from the platen; means being provided to enable the driver upon its return stroke to render said 15 disconnecting means effective.

49. In a typewriting machine, the combination with a revoluble platen and a wheel connected thereto, of a revoluble driver having a pawl to engage the wheel, said pawl 20 having a projection, an annular guide for said projection, said guide having a recess, a spring to cause the projection to enter the recess and the pawl to become disconnected from the wheel, and means to enable the 25 driver to close said recess, so as to permit the driver to turn through more than an entire revolution at one stroke without becoming disconnected from the platen, provision being made to enable the driver during its 30 return stroke to open said recess.

50. In a typewriting machine, the combination with a revoluble platen and a wheel connected thereto, of a revoluble driver having a pawl to engage the wheel, said pawl 35 having a projection, an annular guide for said projection, said guide having a recess, a spring to cause the projection to enter the recess and the pawl to become disconnected from the wheel, and means to enable the 40 driver to close said recess, so as to permit the driver to turn through more than an entire revolution at one stroke without becoming disconnected from the platen; provision being made to enable the driver during its 45 return stroke to open said recess, said recess-closing means including a pivoted arm in the path of a projection on the pawl and movable by said projection to close said recess; said 50 arm being provided with a cam to be engaged by said projection during the return stroke of the driver to swing said closing-arm to open said recess.

51. In a typewriting machine, the combination with a revoluble platen and a wheel 55 connected thereto, of a revoluble driver having a pawl to engage the wheel, said pawl having a projection, an annular guide for said projection, said guide having a recess, a spring to cause the projection to enter the recess and the pawl to become disconnected

from the wheel, and means to enable the driver to close said recess, so as to permit the driver to turn through more than an entire revolution at one stroke without becoming disconnected from the platen; provision being made to enable the driver during its return stroke to open said recess, said recess-closing means including a pivoted arm in the path of a projection on the pawl and movable by said projection to close said recess; said arm being provided with a cam to be engaged by said projection during the return stroke of the driver to swing said closing-arm to open said recess, said closing-arm also serving as a stop to arrest said driver upon its final return 80 to initial position.

52. In a typewriting machine, the combination with a revoluble platen, of a revoluble driver therefor, and an adjustable stop mechanism for limiting the stroke of the driver to 85 either less or more than an entire revolution at will.

53. In a typewriting machine, the combination with a revoluble platen, of a driver therefor, said driver mounted to turn around 90 the axis of the platen, a device operative to arrest the driver only after the latter has turned through more than an entire revolution at one stroke from initial position, and a stop for limiting the stroke of the driver to 95 less than an entire revolution, at will.

54. In a typewriting machine, the combination with a revoluble platen, of a revoluble driver therefor, a stop past which said driver may move, means to enable said driver, after 100 passing the stop once, to be arrested thereby at the succeeding revolution of the driver in the same direction, and a stop for limiting the stroke of the driver to less than an entire revolution, at will.

55. The combination with a revoluble platen, of a stop adjustable about the platen axis, means to enable the platen to be arrested by said stop after the platen has turned during one stroke more than an entire revolution, a second stop also adjustable about the platen axis, for limiting the stroke of the platen to less than an entire revolution, and means for silencing the second stop.

56. The combination with a revoluble platen, of a stop adjustable about the platen axis, means to enable the platen to be arrested by said stop after the platen has turned during one stroke more than an entire revolution, a second stop also adjustable about the platen axis, for limiting the stroke of the platen to less than an entire revolution, and means for silencing the second stop; said stops in the form of pins connected to 115 render either effective and the other ineffective.

57. The combination with a revoluble platen, of a stop adjustable about the platen axis, means to enable the platen to be arrested by said stop after the platen has 120

- turned during one stroke more than an entire revolution, a second stop also adjustable about the platen axis, for limiting the stroke of the platen to less than an entire revolution, 5 means for silencing the second stop; said stops in the form of pins connected to render either effective and the other ineffective, and a rack into which either of said pins may be set.
- 10 58. The combination with a revoluble platen, of a stop adjustable about the platen axis, means to enable the platen to be arrested by said stop after the platen has turned during one stroke more than an entire 15 revolution, a second stop also adjustable about the platen axis, for limiting the stroke of the platen to less than an entire revolution, means for silencing the second stop; said stops in the form of pins connected to render either effective and the other ineffective, and a rack into which either of said pins may be set; both pins yieldingly carried upon an arm which is hung to turn about the platen axis.
- 20 59. In a typewriting machine, the combination with a platen revoluble for line-spacing, of a plurality of stops for arresting the revolution of the platen; and a rack along which said stops are adjustable together; 25 said stops mounted and connected to permit either to be set into effective position and cause the other to be rendered ineffective.
60. In a typewriting machine, the combination with a revoluble platen, of a revoluble 30 driver therefor, a stop out of the path of said driver, a loose interponent to engage said stop and said driver to arrest the latter upon

the second revolution thereof in the same direction at one stroke, and a second stop movable into the path of the driver at will 40 to limit its stroke to less than an entire revolution.

61. In a typewriting machine, the combination with a revoluble platen and a revoluble driver therefor, of a stop adjustable 45 about the axis of revolution of the driver and out of the path of the driver, an interponent in the path of the driver and arrestable by said stop, said interponent loosely revoluble about the axis of the driver, and a second 50 stop also adjustable about the axis of revolution of the driver and movable into the path of the driver at will to limit its stroke to less than an entire revolution.

62. In a typewriting machine, the combination with a platen, of a wheel connected thereto and provided with teeth or notches, a crank mounted to turn concentrically with said wheel, a pawl controlled by said crank, means normally holding said pawl out of 60 engagement with said wheel, means to enable the crank to move the pawl into engagement with the wheel, means to maintain such an engagement during a stroke of the crank through more than an entire revolution back to initial position, and means to limit the first stroke of the crank to either more or less than an entire revolution, at will.
